UNITED STATES PATENT OFFICE.

JAMES WEST, OF LONDON, ENGLAND, ASSIGNOR TO JAMES WEST, GEORGE WEST, AND HENRY JOSEPH WILBERFORCE RAPHAEL, OF SAME PLACE.

COVER FOR PNEUMATIC TIRES.

SPECIFICATION forming part of Letters Patent No. 593,952, dated November 16, 1897.

Application filed April 5, 1897. Serial No. 630,833. (No model.) Patented in France March 25, 1897, No. 263,358.

To all whom it may concern:

Be it known that I, JAMES WEST, a subject of the Queen of Great Britain and Ireland, residing at 5 Teddington Park Road, Teddington, London, in the county of Middlesex, England, have invented Improvements in Covers for Pneumatic Tires, (for which a French patent was granted March 25, 1897, No. 263,358,) of which the following is a specification.

10 This invention of improvements in covers for pneumatic tires has for its object to provide tire-covers of improved constructions designed to prevent or lessen liability to side slipping and at the same time to render the 15 whole or any portion of the wearing-surface easily renewable. For this purpose I construct tire-covers as I shall now proceed to describe with reference to the accompanying drawings, wherein—

20 Figures 1 and 2 are respectively a cross-section and part plan showing a tire-cover constructed according to my invention.

The tread portion of the tire-cover 1, which is or may be of the ordinary light and cheap 25 construction, is formed with several rows of closely-pitched holes 2, which extend entirely through it and which are bushed or reinforced by eyelets 3, of metal or other hard material, that effectually protect the edges of the holes 30 against damage by contact with stones or other obstacles in the road. These eyelets are fitted with studs 4, of suitable material, such as india-rubber or equivalent yielding 35 material, formed at their inner ends with enlarged heads 4^x, that bear against the inner surface of the cover. The studs are made of a larger diameter than that of the eyelets, so that upon being forced through such eyelets they will tightly fit the same, and their outer

40 projecting ends will expand to their normal diameter and fit over the outer ends of the eyelets, so that they will not be liable to be forced inward by contact with the ground, (even when the inner air-tube is deflated,) 45 but, on the contrary, being forced outward by the inner air-tube and being soft and yielding, their outer ends will when in contact with the ground be flattened more or less,

and so become more rigidly and effectually held in place and prevent any leakage of dirt or moisture into the cover or tire. The heads on the inner ends of the studs enable the studs to be effectually held in place by the inner air-tube of the tire and prevent the studs being forced outward through the eyelets by the air-pressure. In the formation of the tire-cover the said holes are not formed by cutting and removing a portion thereof by means of a belt or wad punch, but are formed in such a way as not to destroy any portion of the fiber, being pierced with a suitable tool, which is followed up by the eyelet.

By the construction described it will be seen that each stud is kept in position by two known and controllable forces—viz., (a) the pressure of the inner air-tube, which acts against the shouldered portion of the head of the stud, forcing it tightly against the inner inextensible wall of the cover and so preventing it from being either forced out by excessive pressure from within or from being accidentally or otherwise pulled out from the outside, and (b) the expansive force of the outer projecting portion of the stud on the outside of the cover, which prevents the stud from being forced inward, as well as enabling it to take the weight and the shocks and to transfer the latter softly to the cover instead of to the air-tube. The studs can when worn be nevertheless readily replaced after the cover has been removed from the air-tube. Furthermore, the arrangement of the studs on each side of the center of the head of the cover effectually prevents side slipping. The tire-cover may be provided with any known or suitable means for attaching it to a wheel-rim.

What I claim is—

A pneumatic tire-cover having formed around its tread portion two or more rows of closely-pitched holes each of which extends entirely through the cover itself, eyelets or bushes secured in said holes so as to reinforce the same, and studs of elastic or yielding material extending through said eyelets or bushes and having enlarged heads at their inner ends bearing against the inner side of

the cover and enlarged outer ends projecting beyond the outer side of the cover, said studs being each made of a greater diameter than that of the hole in the eyelet or bush through 5 which it is forced so that its outer projecting end is expanded over the outer end of the said eyelet or bush, substantially as herein described for the purpose specified.

In testimony whereof I have signed my name to this specification in the presence of 10 two subscribing witnesses.

JAMES WEST.
